UNITED STATES PATENT OFFICE.

ANTON DANEK, OF CHICAGO, ILLINOIS.

RUG HOLDER OR STIFFENER.

No. 901,693.

Specification of Letters Patent.

Patented Oct. 20, 1908.

Application filed July 10, 1908. Serial No. 442,843.

To all whom it may concern:

Be it known that I, ANTON DANEK, a resident of Chicago, in the county of Cook and State of Illinois, have invented certain new and useful Improvements in Rug Holders or Stiffeners, of which the following is a full, clear, and exact description.

The invention relates to devices for holding the edges or corners of a rug in flat position.

In rugs, *e. g.*, oriental rugs, the woven fabric is of such a character that its corners or edges will curl in lieu of remaining flat on a floor.

It has heretofore been proposed to sew strips or devices on the rug to prevent the corners thereof from curling. An objection incident to these stiffening devices which were sewed on the rug was that the rug could not be rolled up without detaching the stiffening devices and furthermore it is objectionable in beating or cleaning a rug to do so when the metallic stiffening device is secured thereto.

The invention designs to overcome these objections to such devices and to provide a holding-device which is provided with teeth or means for detachably engaging the rug so that each holder may be placed at any portion of the rug which has a tendency to curl which may be quickly detached when it is desired to clean the rug and which, when in position, will not cause the overlying portions of the rug to project so that it will become worn.

With these objects in view, the invention consists in the several novel features herein-after set forth and more particularly defined by claim at the conclusion hereof.

In the drawings: Figure 1 is a perspective of a rug having several of the improved holding-devices applied thereto. Fig. 2 is a perspective of one of the stiffening-devices. Fig. 3 is a section illustrating the holding-device connected to the under side of a rug. Fig. 4 is a perspective of a modified form of the device.

The holding-device is formed of a narrow strip of flat thin spring-metal, such as steel, sufficiently rigid to hold a portion of a rug

overlying it, taut. The strip *a* is formed of a thin flat strip of metal having points *a'* and *a''* at its ends which extend substantially in the plane of the body of the strip and are adapted to be inserted into the rug to secure the strip on the under side thereof. The teeth on the strip are outwardly pointing so that the device may be connected to and detached from the under side of the rug by flexing to force the points into or out of the rug and so that when the points at the opposite ends of the strip have been inserted into the rug, the strip will be detachably secured to the rug and will hold the edge-portion of the rug from curling. The teeth on the opposite ends of the strip are oppositely pointed so the strip will be held in the rug by the inherent stiffness of the strip.

To attach the strip it will be flexed as indicated in dotted lines Fig. 3, and its points inserted into the rug, and when released, it will flatten itself and be held in the rug as indicated in full lines in said figure, and effectively secure the edge-portion of the rug so it will not curl. By employing a flat strip of spring or resilient metal, the device will be held under the rug and will embed itself in the rug without causing any substantial projection of the rug likely to cause it to become worn.

An important advantage of the improved stiffening device is that it may be readily and quickly applied to whatever portion of the rug may have a tendency to curl. Furthermore, after the strip has been applied to one portion of the rug for a period, it may be applied to some other portion, if the former has become so that it will inherently remain flat. So also, the fastening-device may be detached from the rug when the latter is to be cleaned or when it may be desired to roll up the rug. By employing teeth extending outwardly or longitudinally of the strip and substantially in the plane of the strip, the teeth will not pass through the fabric of the rug and will be invisible.

It is desirable where the edge or corner of the rug is thinly woven to employ two teeth as shown at *a''* to cause the rug to be more firmly held by the strip.

In the modification illustrated in Fig. 4, both ends of the stiffening strip are provided with a pair of teeth a^2 .

Having thus described the invention, what I claim as new and desire to secure by Letters Patent, is:

A holding-device for rugs formed of a thin strip of resilient metal and provided with op-

positely extending teeth disposed to engage and for removably securing both ends of the strip in a rug.

ANTON DANEK.
